CLAIM

The ornamental design for an amphibious sport aircraft with wings stowed, as shown and described.

DESCRIPTION

FIG. 1 is a right front perspective view of an amphibious sport aircraft with wings stowed showing our new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

The structural elements depicted by broken lines have been shown for the purpose of illustrating portions of the amphibious sport aircraft with wings stowed that form no part of the claimed design.
